METHOD FOR PREPARING AN OLEFIN
POLYMERIZATION FEED STOCKRaymond L. Heinrich, Baytown, Tex., assignor, by
mesne assignments, to Standard Oil Develop-
ment Company, Elizabeth, N. J., a corporation
of DelawareNo Drawing. Application June 23, 1948,
Serial No. 34,832

6 Claims. (Cl. 260—683.15)

1

The present invention is directed to an improved method for polymerizing olefins in the presence of a Friedel-Crafts catalyst. More particularly, the invention has to do with the preparation of a feed stock for catalytic conversion operations. In its more specific aspects, the invention is concerned with the preparation of a feed stock for catalytic conversion operations from naphthas containing olefins and oxygenated organic compounds.

Processes in which hydrocarbons are subjected to oxidation result in products including oxygenated organic compounds and low molecular weight hydrocarbons. The oxygenated compounds usually include the ketones, organic acids, aldehydes, esters, and the like, while the hydrocarbons produced from such oxidation reactions may include the olefins, both the mono- and diolefins, paraffinic and naphthenic hydrocarbons, and possibly others. This mixture of oxygenated organic compounds and hydrocarbons, while a veritable storehouse of valuable materials in itself, is not particularly useful until the materials are separated according to type. For example, the oxygenated organic compounds of the type mentioned in admixture with each other or with the hydrocarbons are not particularly useful, but taken alone are quite valuable. Similarly, the olefinic hydrocarbons in admixture with the other hydrocarbons and with the oxygenated organic compounds are not as valuable as the olefinic hydrocarbon alone or simply in admixture with other hydrocarbons.

The reaction of carbon monoxide and hydrogen over certain catalytic material in the so-called Fischer-Tropsch synthesis likewise produces a reaction product including hydrocarbons and oxygenated organic compounds of the type mentioned. The reaction product of carbon monoxide and hydrogen produced in the presence of an iron catalyst contains olefins, paraffins, aromatics besides oxygenated organic compounds such as those found in the oxidation reaction mentioned above. The resolution of a mixture of hydrocarbons and oxygenated compounds into component parts has presented the industry with a serious separation problem. It is important to obtain the oxygenated organic compounds separated from the hydrocarbons since they are valuable chemical raw materials, and it is also im-

2

portant to obtain the hydrocarbons substantially free of the oxygenated organic compounds. When the oxygenated organic compounds are present in olefinic hydrocarbons, the hydrocarbons are less valuable as feed stocks to catalytic conversion operations than when the olefinic hydrocarbons are substantially free of the oxygenated compounds.

Numerous methods have been suggested in the prior art of treating olefinic hydrocarbons containing oxygenated organic compounds. Many of the methods suggested are open to serious economic objections in view of the tedious steps necessary to remove the oxygenated organic compounds from the naphtha or because chemicals approaching in value the value of the oxygenated compounds are required to treat these naphthas containing olefins and oxygenated compounds.

It is, therefore, the main object of the present invention to provide a process for treating naphthas containing olefins and oxygenated organic compounds to make such naphthas suitable for use in catalytic conversion operations.

Another object of the present invention is to provide an improved polymerization process in which olefinic naphthas containing oxygenated organic compounds and contaminants are treated to cause removal of the contaminating materials as high boiling reaction products.

It has been found that by treating olefinic naphthas containing oxygenated organic compounds with reactive sulfides such as illustrated by hydrogen sulfide higher boiling materials are formed which may be separated from the olefinic naphtha by distillation. Following the distillation operation, the naphthas may be polymerized in the presence of a Friedel-Crafts catalyst.

Accordingly, the present invention may be described briefly as involving the treatment of an olefinic naphtha containing oxygenated organic compounds with a reactive sulfide at a temperature in the range from about 40° to 250° F. and at a reaction time ranging upwardly from about 1 minute to about 6 hours under conditions to cause the formation of a reaction product including material boiling substantially above the boiling range of the olefinic naphtha undergoing treatment. Following the treatment with the reactive sulfide the naphtha may then be subjected to treatment with an alkaline solution to

remove unreacted sulfide and then subjected to distillation to recover a naphtha boiling substantially in the boiling range of the feed naphtha while the reaction product including the deleterious bodies is removed as a heavier fraction. The naphtha recovered after the foregoing treatment with a reactive sulfide may then be subjected to polymerization in the presence of a Friedel-Crafts catalyst such as illustrated by aluminum chloride at a temperature in the range between about 50° and 250° F., preferably about 175° F., to produce a polymer including fractions boiling in the lubricating oil boiling range and having lubricating oil characteristics. The polymer may be distilled to separate said lubricating oil fractions which then may be used in lubricating internal combustion engines and the like.

The reactive sulfide employed in the practice of the present invention is preferably hydrogen sulfide, but other sulfides such as the alkali metal sulfides as illustrated by lithium, sodium, and potassium sulfides, bisulfides and polysulfides may be used. Similarly, the ammonium sulfides and bisulfides may also be employed. The phosphorus sulfides such as exemplified by phosphorus pentasulfide, phosphorus hexasulfide, and phosphorus heptasulfide may also be used. Many other reactive sulfides of the type mentioned could also be mentioned as being suitable in the practice of my invention.

It is desirable to cause initiation of the reaction by including in the reactive sulfide, such as hydrogen sulfide, an acidic material such as illustrated by gaseous hydrogen chloride. While gaseous hydrogen chloride is preferred as the activating material, other acidic bodies such as the non-gaseous strong acids such as sulfuric acid, nitric acid, as well as the other halogen acids as exemplified by hydrobromic, hydroiodic, and the like may be used.

The Friedel-Crafts catalyst employed in the polymerization step of my invention will preferably be aluminum chloride but other Friedel-Crafts catalysts such as titanium tetrachloride, zirconium chloride, ferric chloride, aluminum bromide and many other well known Friedel-Crafts catalysts may be used.

The invention will be further illustrated by reference to the following example in which a naphtha boiling in the range between 100° and 450° F. was obtained from a synthesis process in which carbon monoxide and hydrogen were reacted over an iron oxide catalyst to produce a product. The product was distilled to recover a fraction in the afore-mentioned boiling range. This fraction was then treated as follows: Hydrogen sulfide containing about 1 mol per cent of hydrogen chloride was passed rapidly into 1000 volumes of vigorously stirred naphtha for 4 hours at 75° F. and at atmospheric pressure. The resulting product after this reaction time was caustic washed and distilled in the presence of steam to recover a fraction corresponding to 70% of the treated naphtha, a second fraction corresponding to 70 to 96% of the treated naphtha, and a third fraction amounting to 4% of the treated naphtha which was a viscous, black material. Portions of the 70% overhead fraction and the total 96% overhead fraction were polymerized in the presence of aluminum chloride at a temperature in the range between 50° and 250° F. to obtain a high boiling, high molecular weight polymer having lubricating oil characteristics. This polymer was then tested to determine its viscosity and viscosity index.

5 The specific conditions under which the polymerization was conducted, the amount of catalyst employed, and the yields and tests of the products are presented in the following table:

Table I

Charge Stock	Untreated Naphtha	0-96% Overhead Treated Naphtha	0-70% Overhead Treated Naphtha
Polymerization Temp., °F.	100	100	100
Polymerization Time, Mins.	120	60	60
AlCl ₃ Catalyst, Wt. Per Cent of Olefins Charged	14.8	14.0	14.0
15 Polymer Yield, Wt. Per Cent of Olefins Charged	21.0	40.0	48.7
Polymer Yield, Wt. Per Cent of Untreated Naphtha	11.5	18.9	16.1
Sludge, Wt. Per Cent of Olefins Charged	34.8	40.7	38.0
<i>Tests on Polymer</i>			
Viscosity at 210° F., S. S. U.	54.4	56.3	
Viscosity Index	84	84	84

25 It will be seen from the foregoing data that when polymerizing the untreated naphtha, the 96% overhead fraction, and a 70% overhead fraction, from the treated naphtha comparative results were obtained which show that substantially greater yields of polymer are obtained from the treated naphtha than from the untreated naphtha. The data also show that the polymer produced from the treated naphtha has a high viscosity index. The viscosity and viscosity index of the untreated naphtha were not determined, but prior experience has shown that such untreated naphthas when polymerized result in substantially lower quality product.

40 Additional runs were then made on a naphtha obtained by distilling the product resulting from a synthesis reaction in which carbon monoxide and hydrogen were reacted over an iron oxide catalyst under synthesis conditions to produce a product including oxygenated organic compounds and hydrocarbons. This distilled naphtha had a boiling range from 110° to 400° F. and was treated in one instance with an aqueous alkaline solution including sodium hydroxide and in another instance in accordance with the present invention with hydrogen sulfide and then washed with a portion of the same aqueous solution of 45 sodium hydroxide. The sodium hydroxide solution was separated from the two naphthas and they were then separately polymerized in the presence of aluminum chloride at a temperature in the range given before and under conditions to form a polymer and an aluminum chloride sludge. The aluminum chloride sludge was separated from the polymer and the yield of the two determined. The unreacted naphtha remaining from the first polymerization was then 50 subjected to a second polymerization treatment under similar conditions to produce a polymer and aluminum chloride sludge. The yields of the two were determined and the product of the second polymerization was then subjected to tests 55 after distilling into a lubricating oil fraction and a sublube oil fraction.

60 The specific conditions of the first and second polymerizations including the amount of aluminum chloride employed per volume of charge, the reaction time and the temperatures are given in the following Table II. The table also presents the tests on the products of the first and second polymerizations and gives in detail the inspection characteristics of the product of the second 65 polymerization.

It will be seen from the foregoing data in Table II that substantially greater yields of products are produced in accordance with the present invention than when polymerizing the raw naphthas which had been merely treated with sodium hydroxide solution. For example, the amount of lubricating oil from the first and second polymerizations increased from 74 volumes to 111 volumes when proceeding in accordance with the present invention. Moreover, the product produced in the first polymerization in accordance with the present invention was of a higher quality than the quality of the product from the first polymerization of the naphtha which had been merely treated with sodium hydroxide as shown by viscosity index data.

Another set of runs were carried out on a naphtha obtained by distilling the product resulting from a synthesis reaction in which carbon monoxide and hydrogen were reacted over an iron oxide catalyst under synthesis conditions to produce a product containing oxygenated organic compounds and hydrocarbons. This distilled naphtha had a boiling range from 140° to 400° F. and was separated into two portions. One portion was washed twice with 100 volume percent of 10 weight percent sodium hydroxide and distilled. The other portion was washed with caustic solution, contacted with hydrogen sulfide containing a trace of hydrogen chloride, washed again with caustic solution, and distilled. The two treated fractions were then separately poly-

merized in the presence of aluminum chloride to produce a high molecular weight polymer and an aluminum chloride sludge. The conditions used in the treating and polymerization steps and analyses and tests of the materials before and after polymerization are given in Table III, following:

¹ H₂S-HCl mixture bubbled through naphtha for one hour at about 80° F.

It will be noted from the foregoing data that the content of oxy organic compounds in the redistilled naphtha in both cases was substantially the same showing that the treatment of the naphtha with sodium hydroxide and with hydrogen sulfide-hydrogen chloride mixture did not effect a much greater removal of the materials from the naphtha than the sodium hydroxide when used alone. It is to be noted that the distribution of olefins by structural types in the two treated naphthas is approximately the same. Therefore, it is indeed surprising that treatment of a naphtha containing oxygenated organic compounds with hydrogen sulfide and hydrogen chloride should result in improved results when the naphtha is subsequently polymerized in the presence of aluminum chloride. Thus, it will be further observed that, when using substantially the same temperature conditions used in the treatment illustrated by the data in Table II but when employing a somewhat higher ratio of aluminum chloride to treated naphtha as shown in Table III, a higher yield of lubricating polymer was obtained.

It has been mentioned that various active sulfides, of which specific examples have been given, may be used in my invention. It is also possible to employ naphtha fractions which contain active sulfides and to use these materials in producing feed stocks which are valuable in catalytic conversion operations. For example, an oxygen-containing olefinic naphtha may have added to it olefin- and sulfur-bearing fractions from petroleum refining operations. Such fractions may include either liquids or gases containing hydrogen sulfide or mercaptans and the like. Similarly, the alkali metal sulfides may be found in treating

solutions employed in petroleum refining operations such as sodium sulfides and sodium mercaptide solutions which are quite commonplace in refining operations.

The nature and objects of the present invention having been fully described and illustrated, what I wish to claim as new and useful and to secure by Letters Patent is:

1. A method for preparing a feed stock for a catalytic polymerization operation which comprises contacting a naphtha containing olefins and oxygenated organic compounds with hydrogen sulfide at a temperature in the range between 40° and 250° F. for a time sufficient to form a reaction product including material boiling above the boiling range of the naphtha and unreacted material, subjecting said contacted naphtha to a separation treatment to separate therefrom said reaction product and recovering from said separation treatment a fraction suitable for use as a feed stock in a catalytic polymerization operation.

2. A method in accordance with claim 1 in which the separation treatment is a distilling operation.

3. A method for preparing a feed stock for a catalytic polymerization operation which consists of contacting a naphtha boiling in the range between 110° and 450° F. and containing olefins and oxygenated organic compounds with hydrogen sulfide at a temperature in the range between 40° and 250° F. and for a time in the range between 1 minute and 6 hours to form a reaction product including material boiling above the boiling range of the naphtha, distilling said contacted naphtha into a fraction boiling in the boiling range of said naphtha and a fraction boiling outside said boiling range of said naphtha and recovering said fraction boiling in the boiling range of said naphtha for use as a feed stock in a catalytic polymerization operation.

4. A method for producing a high molecular weight polymer boiling in the lubricating oil boiling range which comprises contacting a naphtha containing olefins and oxygenated organic compounds and boiling in the range between 100° and 450° F. with hydrogen sulfide at a temperature in the range between 40° and 250° F. for a time in the range between 1 minute and 6 hours to form a reaction product including material boiling above the boiling range of the naphtha, distilling said contacted naphtha into at least two

fractions, one boiling in the boiling range of said feed naphtha and one boiling above the boiling range of said feed naphtha, subjecting said distilled fraction boiling in the boiling range of said

5 feed naphtha to polymerization conditions including contact with a Friedel-Crafts catalyst under conditions to form a product including a high molecular weight polymer in the lubricating oil boiling range, and distilling said product to recover said polymer in said lubricating oil boiling range.

6. A method in accordance with claim 4 in which the Friedel-Crafts catalyst is aluminum chloride.

15 6. A method for preparing a high molecular weight polymer having lubricating oil characteristics which comprises treating a naphtha fraction boiling in the range between 110° and 450° F. and containing olefins and oxygenated organic compounds with hydrogen sulfide for about 6 hours to form a reaction product including material boiling outside the boiling range of said naphtha, contacting said treated naphtha with an alkaline solution, distilling the treated naphtha into a first fraction boiling in the range of said feed naphtha and a second fraction boiling outside the range of said feed naphtha, contact-

20 25 in said first fraction with a Friedel-Crafts catalyst under polymerization conditions to form a product including a polymer in the lubricating oil boiling range and distilling said product to recover a fraction having lubricating oil characteristics.
